UNITED STATES PATENT OFFICE.

WILLIAM BLACKER, OF STALEYBRIDGE, ENGLAND.

TREADLE-HAMMER.

1,297,990.

Specification of Letters Patent.

Patented Mar. 25, 1919.

Application filed February 19, 1918. Serial No. 218,051.

To all whom it may concern:

Be it known that I, WILLIAM BLACKER, a subject of the King of Great Britain and Ireland, residing at 62 Stocks Lane, Staleybridge, in the county of Lancaster, England, engineer, have invented new and useful Improved Treadle-Hammers, of which the following is a specification.

This invention relates to an improved treadle hammer and in particular to that type of hammer in which the head is swung on parallel arms or their equivalent.

The attached drawings show the improved treadle hammer.

15 In the said drawings:—

Figure 1 is a side elevation of the hammer.

Fig. 1^a is a fragmentary detail view showing the connection between one end of the 20 rail *d* and one of the tubes *c*.

Fig. 2 is a detail plan view.

Fig. 3 shows a front elevation omitting certain of the parts.

I make use of suitable end standards *a*, *a*, 25 which are attached to the base *b*, or otherwise supported, and such end standards are suitably stayed the requisite distance apart as for example by stays *b'*, *b'*. A treadle device is combined with the base casting, 30 or otherwise sustained, and same may consist of a bent tube *c* fulcrumed at *c'*, *c'* on either side of said base *b* and passing around the front of the hammer and clear of the anvil or block.

35 Across this treadle, extends a rail *d* which may be round or of other cross section, and same is firmly attached at each extremity to the tube member of the treadle *c* by U-bolts and nuts *d'* (see the detail view Fig. 1^a), or 40 other means.

The end standards *a*, *a*, are bored and if necessary bushed or otherwise prepared to receive a slidable frame which may consist of a number of horizontal shafts or rods, as 45 for example three shafts or rods *e*, *e'*, *e''* which are of greater length than the distance between the end standards. The shafts or rods *e*, *e'*, *e''* are sustained or carried by end bars or uprights *f* a connection being effected by nuts or other means. A transverse steel or other bar *g* is also built up in the frame and this is provided with teeth *g'* over a portion of its length. The shafts or rods *e*, *e'*, *e''* are 55 conveniently round in cross-section so as to slide easily through the end standards

and to turn in the stout uprights *f*, and the complete frame is moved left or right as required by means of a spur pinion *g*² gearing with the rack teeth, said spur pinion *g*² being supported in brackets *g*³ bolted to the frame. Any other form of gear mechanism may be used for traversing the frame. Upon the two upper horizontal shafts or rods I mount the parallel arms, 60 and, where two parallel arms such as *h*, *h'* only are employed one is arranged in connection with each shaft or rod. The manner of attaching the parallel arms may be greatly varied, as for example the tapered 65 extremities may fit tapered holes in enlargements formed on the shafts, the arms being keyed in place; or bored sleeves such as *h*², *h*³, may be fitted on the shafts and the tapered or shaped ends of the arms may be 70 held in place by keys or otherwise. These bored sleeves are firmly pinned on the shafts *e*, *e'* as shown by Fig. 1. In connection with the lower parallel arm *h'*, or more conveniently with the supporting sleeve *h*³, 75 I form a bracket or jaws *h*⁴, *h*⁴, or other preparation, and such brackets or jaws are bored, and jointed thereto at *h*⁵, is a pendent bar or rod *i* the same having a suitable bored head or stop collar *i'*. A coiled 80 spring *j* surrounds this pendent bar or rod *i*. The lower extremity of the pendent bar or rod *i* passes through a small bored rocking plate or swivel abutment *i*² having trunnions *i*³, *i*³, which rocking 85 plate or abutment is accommodately carried by two small levers or brackets *i*⁴, *i*⁴ keyed or attached to the third or lower shaft or rod *e*². As thus, the coiled spring *j* lies disposed and confined between the head or 90 stop collar *i'*, and the rocking plate or swivel abutment *i*², and its function is to return or 95 elevate the hammer head and to maintain same in raised position. I may vary the manner of holding the lower extremity of 100 the pendent bar or rod.

Jointed to the lower parallel arm, or to some suitable attachment in connection therewith (as for example to the pivoted link *k*), is an adjustable connecting rod *l* 105 which terminates in a bracket *l'* or the like supporting a bowl or runner *l*² which engages below the treadle rail *d*, such connecting rod device *l* effecting the swinging of the hammer head when the treadle is worked. 110

The entire traveling frame *e*, *e'*, *e''*, *g*, *f*, *f* can be adjusted laterally so as to place the

hammer head at any position over the anvil, by simply working the rack and pinion gear, or the mechanism used in lieu thereof.

In order not to interfere with the strength 5 of the blow or the arc through which the head is swung according as the depth or size of the work on the anvil varies, mechanism is provided whereby the hammer head can be raised or lowered from a mean position 10 (or raised from the lowest position) and such mechanism takes the form of devices which act on the coiled spring. By way of example, I may mount a crank or arm m on the third or lower shaft or rod 15 e^2 which crank or arm when moved up, would (if the bar or rod i were immovably held) act to bring about compression of the coiled spring j , and so the hammer head is raised. Such crank or arm m can be acted 20 on by a connecting rod or link n jointed to a control lever o fulcrumed at o' on one of the upright bars f of the frame, and such control lever o carries a spring pressed 25 detent or locking appliance o^2 fulcrumed at o^3 and capable of engaging a toothed quadrant p or equivalent device fixed also to the upright bar or otherwise carried. The locking 30 detent o^2 is easily withdrawn by acting on the guided rod or spindle o^4 as is clear from an inspection of the detail plan Fig. 2.

From the foregoing, it is obvious that the sliding frame e , e' , e^2 , g , f , f , may be easily and quickly traversed to bring the hammer head to any position over the anvil and that 35 the elevated position of the hammer head can be regulated or adjusted as required by the mere movement of the control lever o , and the setting secured. As the hammer head is swung by acting on the treadle c the shafts e , e' turn or rotate slightly as 40 required.

In the matter of mere constructional detail I may make considerable variation and I might if desired use more than one coiled

controlling spring making suitable modifications to that end.

I declare that what I claim is.

1. A treadle hammer having a head, parallel arms for said head, a sliding frame carrying the parallel arms, a traversing device for said frame, hammer head adjusting means carried on said sliding frame, locking means therefor, a foot treadle and a connection to work the parallel arms as set forth.

2. A treadle hammer, having a sliding frame, parallel swing arms mounted thereon, a central hammer raising rod, a spring device in connection therewith, means to work such hammer raising rod, and hammer adjusting mechanism carried on the sliding frame and means to lock such hammer adjusting mechanism for the purpose described.

3. A treadle hammer comprising a frame, parallel arms pivoted to said frame, a hammer head carried by said arms, a foot treadle operatively connected to said arms, a second frame slidable on the first frame, a bar connected to said arms, a spring surrounding said bar and acting on said arms, and means for adjusting the tension of said spring to vary the normal position of said arms.

4. A treadle hammer comprising a frame, parallel arms pivoted to said frame, a hammer head carried by said arms, a foot treadle 75 operatively connected to said arms, a second frame slidable on the first frame, a bar connected to said arms, a spring surrounding said bar and acting on said arms, a quadrant rack mounted on the first frame, a lever 80 operatively connected to said spring for adjusting its tension, and a pawl carried by said lever and engageable with said rack for locking said lever in adjusted position.

In testimony whereof I have signed my 85 name to this specification.

WILLIAM BLACKER.
